FIGURINE OR THE LIKE

Filed Dec. 12, 1950

FIG. 1

FIG. 2

INVENTOR
SEYMOUR BLUM

BY Tennesse G. Cristad
ATTORNEY

UNITED STATES PATENT OFFICE

167,442

FIGURINE OR THE LIKE

Seymour Blum, Brooklyn, N. Y.

Application December 12, 1950, Serial No. 13,401

Term of patent 14 years

(Cl. D29—23)

To all whom it may concern:

Be it known that I, Seymour Blum, a citizen of the United States, a resident of the county of Kings, Borough of Brooklyn, and city and State of New York, have invented a new, original, and ornamental Design for a Figurine or the like, of which the following is a specification, reference being had to the accompanying drawings, forming part thereof.

Figure 1 is a side elevational view of a figurine or the like, showing my new design;

I claim:

The ornamental design for a figurine or the like, substantially as shown.

SEYMOUR BLUM.
